PIEZOELECTRIC CRYSTAL HOLDER

Alan James Perkins, London, and Walter George
Roberts, Hove, England, assignors to Simmonds
Aeroaccessories Limited, London, England

Application September 28, 1943, Serial No. 504,170
In Great Britain October 1, 1942

2 Claims. (Cl. 171—327)

This invention relates to piezo-electric crystal holders or mountings.

In the production of piezo-electric crystal holders, whether of the simple air-gap, pressure air-gap or pressure type, it is often necessary to process the crystal and then to test it in association with its electrodes in the holder in which it is to be mounted finally. As this processing and testing may have to be repeated several times, it is important that the performance of the mounted crystal shall be consistent. It is also important that when the crystal has been adjusted finally to have a desired performance it can be mounted in its holder and the holder permanently sealed without alteration to the performance of the crystal.

It is the principal object of this invention to provide a piezo-electric crystal holder which is adapted to maintain the electrical characteristics of the crystal substantially constant.

A further object of the invention is to provide a holder which is of robust construction and wherein the crystal and its electrodes are securely held against relative movement.

A still further object of the invention is to provide a mounting for a piezo-electric crystal such that the electrical parameters of the crystal may be readily adjusted before the outer casing or cover is fitted and are not affected during the fitting of such outer casing or cover.

Other objects and advantages of the invention will become apparent during the course of the following description of the drawing in which

Fig. 1 is a perspective view of the improved crystal holder with the cover thereof removed to show the construction more clearly.

Fig. 2 is a perspective view of a part of the holder.

Fig. 3 is a plan view of a part of the holder, and

Fig. 4 is a central vertical section through a complete holder.

In the improved piezo-electric crystal holder in accordance with the present invention the crystal and its associated electrodes are housed within a shallow tray member of insulating material and the said tray member is a close sliding fit in an outer casing or cover.

Referring to the drawing the improved holder comprises generally a tray member 10 within which the crystal and its associated electrodes are housed and a cover member 11.

The tray member 10, see Fig. 3, is a rectangular moulding comprising bottom, side and end walls of suitable insulating material. At the corners of the outer end of the tray are metal terminal

blocks 12 secured in position by the threaded ends of contact pins 13 which extend through apertures in the outer end wall of the tray 10 and are screwed into the said blocks. An insulating block 14, preferably integral with the tray member 10, extends between the metal blocks 12, and the insulating block 14 forms with the side walls and inner end wall of the tray member 10 a square crystal and electrode holding chamber. Located in the bottom of the said chamber is a thin metal contact plate 15 which has an arm 16 extending beneath one of the metal blocks 12 whereby electrical connection is made between the lower electrode 17 and one of the contact pins 13. The crystal 27 and upper and lower crystal electrodes 18 and 17, are a close fit in the said chamber and the crystal is clamped between the electrodes 17 and 18 by a concave spring strip 19 which bears against the upper electrode 18 at its centre portion, one end of the strip being secured by a set screw 20 within a recess in the inner end wall of the tray member 10 and the other end of the strip being screwed or otherwise secured to the insulating block 14 at the outer end of the tray. The set screw 20 allows the pressure exerted by the spring to be readily adjusted. The said spring, at its outer end, is formed with an arm 21 which is screwed or otherwise attached to the other metal block 12 whereby electrical connection is made between the upper electrode 18 and the other contact pin 13.

The crystal, its electrodes and the clamping spring are housed entirely within the confines of the tray member and it will be appreciated that, since the crystal and its electrodes are a close fit in the crystal chamber of the tray member and are clamped together by the spring, movement of the crystal and its electrodes relatively to the tray member is effectively restrained and there is little or no danger of the electrical parameters of the crystal being altered by shocks or other violent movements. As shown in Figs. 1 and 4 a reducing frame 25, shown in Fig. 2, may be readily fitted within the tray 10, whereby it can be adapted to house crystals and electrodes of smaller size.

The outer casing or cover 11 comprises a rectangular box-like member of suitable insulating material and open at one end whereby the tray member can be slid thereinto. The tray member is a close fit in the casing so that the tray member and the outer casing support and strengthen one another. The tray member 10 may be removably secured to the casing 11 by screws 21, see Fig. 4, passing through the

end wall of the casing, and the tray member may be quickly secured within or removed from its casing without affecting the electrical parameters of the crystal.

To allow the tray member 10 to be readily and effectively sealed within the outer casing 11, the tray member 10 is advantageously formed near its outer end with a peripheral flange 22, the outer casing being recessed as at 23 at its open end to provide a ledge 26 against which flange 22 abuts and forms a groove 24 for receiving suitable sealing material.

We claim:

1. A piezo-electric crystal holder comprising an open ended cover member, a tray member fitting in said cover member, said tray member having a bottom, and side and end walls, one of said walls being dimensioned to engage and close the open end of said cover member when said tray member is inserted in said cover member, said tray member being dimensioned to receive therein with a close fit a crystal and its associated electrodes, means retaining said crystal and electrodes in intimate contact within said tray member, a

pair of terminal members extending through the said end wall of the tray member, and means for making electrical connection between the said electrodes and said terminal members.

5 2. A piezo-electric crystal holder comprising an open ended cover member, a tray member fitting in said cover member, said tray member having a bottom, and side and end walls, one of said walls being dimensioned to engage and close the open end of said cover member when said tray member is inserted in said cover member, said tray member being dimensioned to receive therein with a close fit a crystal and its associated electrodes, a resilient member supported by said tray member and yieldingly engaging the electrode-crystal assembly to maintain the latter against upward displacement in said tray member, a pair of terminal members extending through the said end wall of the tray member, and means for making electrical connection between the said electrodes and said terminal members.
